US00D976207S

(12) **United States Design Patent** (10) **Patent No.:** **US D976,207 S**
Wu (45) **Date of Patent:** **** Jan. 24, 2023**

(54) **FOLDABLE WIRELESS CHARGER**

(71) Applicant: **Guanyuan Shengye (Shenzhen) Intelligent Technology Co., Ltd., Shenzhen (CN)**

(72) Inventor: **Manfang Wu, Heyuan (CN)**

(**) Term: **15 Years**

(21) Appl. No.: **29/850,532**

(22) Filed: **Aug. 22, 2022**

(51) **LOC (14) Cl.** **13-02**

(52) **U.S. Cl.**

USPC **D13/108**

(57) **CLAIM**

The ornamental design for a foldable wireless charger, as shown and described.

DESCRIPTION

FIG. 1 is a first perspective view of a foldable wireless charger showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 1.

The broken lines shown in the drawings depict portions of the foldable wireless charger that form no part of the claimed design.

1 Claim, 9 Drawing Sheets
